UNITED STATES PATENT OFFICE.

FRANK M. JACOBS, DECEASED, LATE OF ATCHISON, KANSAS, BY HENRY JACOBS,
ADMINISTRATOR, OF ATCHISON, KANSAS.

FIRE-BOX FOR BOILERS.

1,135,114.

Specification of Letters Patent. Patented Apr. 13, 1915.

Application filed May 20, 1914. Serial No. 839,698.

To all whom it may concern:

Be it known that I, HENRY JACOBS, a citizen of the United States, and a resident of Atchison, in the county of Atchison and 5 State of Kansas, am the administrator of the estate of FRANK M. JACOBS, deceased, late a citizen of the United States, and resident of Atchison, Kansas, who had invented certain new and useful Improvements 10 in Fire-Boxes for Boilers, of which the following is a description, reference being had to the accompanying drawings, which form a part of the specification.

The invention relates more particularly 15 to fire-boxes for the locomotive type of boilers, although it is readily apparent that certain features of the invention may be employed in connection with boilers of other types.

20 One object of the invention is to provide a more efficient fire-box by the provision of heating surfaces in and around the combustion chamber, composed of water tubes arranged to constitute the side walls of the 25 fire-box or combustion chamber as well as an intermediate wall; the water tubes arranged to constitute the side walls being employed instead of the usual stayed side and crown sheets.

30 Another object of the invention is to provide a fire-box wherein the water tubes which constitute the side walls as well as an intermediate wall, will connect with a hollow mud-ring or header at the bottom of 35 the fire-box or combustion chamber and with headers or chambers at the top, substantially as and in the manner illustrated in the accompanying drawings.

By reason of the arrangement of the 40 water tubes, as set forth in the accompanying drawings, a material increase of heating surface is provided, and the combustion chamber divided into two compartments by the intervening wall or partition composed 45 of water tubes, which, however, are so arranged as not to materially decrease the grate area, but increase the surface or surfaces exposed to the hot gases of combustion; the water tubes or heating surfaces being so arranged, however, as not to interfere 50 with or baffle the hot gases in their passages through the fire-flues of the boiler.

Another object of the invention is to 55 eliminate the difficulties heretofore encountered in connection with the staying of the

fire-box and shell sheet, which is accomplished by replacing them with water tubes and chambers or headers at the top and with a heavy hollow mud-ring at the bottom; thus providing a non-explosive fire-box, which may also be readily applied to any ordinary existing locomotive boiler.

The various advantages above enumerated, as well as other advantages inherent in the construction, will be more readily understood from the following detailed description of the accompanying drawings, wherein:

Figure 1 is a longitudinal sectional view of the improved fire-box taken on the line *a—a* of Fig. 2, looking in the direction of the arrows. Fig. 2 is a vertical sectional view taken on the line *b—b* of Fig. 1, looking in the direction of the arrows.

In the particular exemplification of the 75 invention as illustrated in the drawings, only a portion of the cylindrical barrel or shell 3 of the boiler is shown, and this shell is secured to the one-piece throat-sheet 4. While the throat-sheet 4, in the particular 80 construction illustrated, has been shown as a one-piece member, it will be readily understood that the throat-sheet may be altered to fit the boiler-shell of the locomotive to which the improved fire-box is intended 85 to be attached.

In the drawings, Fig. 1, the throat-sheet 4 is preferably shown secured by the rivets 5 to the boiler-shell 3, and to the front head and flue-sheet 6, by means of the rivets 7. 90 The flue-sheet 6 is cut away so as to conform with the lower outside contour of the drums or headers 8, 8^a, as more clearly set forth in Fig. 2, so as to leave the ends of the drums or headers 8, 8^a, open and in communication with the upper or steam portion of the boiler. The flue-sheet 6 is preferably provided with an off-set or dished portion 6^a, which constitutes the flue or fire-tube receiving area; the flues 9 being 100 preferably secured to the flue-sheet by welding them integrally, either autogenously or electrically. The flue-sheet is also preferably provided with the rearwardly presented portion 6^b, see Fig. 1, in order to 105 provide a rivet flange over the top contour of the fire-box shell.

The upper or crown surface of the fire-box is formed by a header shown in the nature of a series of transversely curved sheets 110

8, 8, 8^a, 8^a, extending throughout the length of the fire-box, with the convexed surfaces presented toward the gases. The sheets, as is very clearly shown in Fig. 2, practically 5 constitute the lower surface of the top header of the fire-box. The sides of the sheets which constitute the side portions 8, 8, of the header, are shown riveted at 10, 10, to the outer shell of the fire-box, while 10 the opposite sides, as well as the sides of the intermediate plates or portions 8^a, 8^a, are secured together with an intermediate stay sheet or member 11, to which are also preferably secured the sling stays 12. The upper 15 ends of the sling stays 12, are pivotally secured to the members 13, which are properly secured, as at 14, to the outer shell. A sufficient number of stays 12 are provided throughout the length of the shell sections 20 as clearly shown in Fig. 1. It is evident from the construction shown and described, where the top drum or header is formed with the outer fire-box shell constituting one 25 wall of the header, that circulation may be had throughout the entire compartment or chamber intermediate of the supporting stays.

The mud-ring 15 is preferably in the nature of a hollow rectangular frame having 30 a central longitudinal portion 15^a, as very clearly shown in Fig. 2, and two side hollow longitudinal portions 15^b, 15^b, which are adapted to form the bottom header for the water tubes now to be described.

35 The water tubes 16, 16^b, are secured to the side longitudinal members or portions 15^b, 15^b, of the mud-ring, and, therefore, constitute the inner side walls of the fire-box; while the water tubes 16^c are secured to the 40 central longitudinal portion 15^a of the mud-ring and constitute a central wall in the fire-box.

The mud-ring 15 has its ends or transversely extending portions cast solid, with 45 the exception of the upwardly presented openings shown in dotted lines at 17 in Fig. 1. These openings effect communication between the hollow chambers of the longitudinal portions or members of the 50 mud-ring and the water-legs arranged at opposite ends of the fire-box; the front water-leg being formed by the throat-sheet 4 and the flue-sheet 6, while the rear water-leg is formed by the door-sheet 18 and the 55 back head 19.

The upper surfaces of the longitudinal portions or members of the mud-ring 15 are provided with suitable openings or holes which receive the lower ends of the water 60 tubes 16, 16^b, and 16^c, see Fig. 2; the holes or openings in the central longitudinal portion 15^a of the mud-ring, being preferably arranged in the staggered manner clearly shown in Fig. 2. The bottom surfaces of 65 the longitudinal portions or hollow mem-

bers of the mud-ring are provided with openings normally closed with suitable threaded plugs as clearly shown at 20; these openings in the bottom surfaces being preferably arranged in alinement with the 70 openings in the top surfaces of the longitudinal members or portions.

The water tubes 16, 16^b, and 16^c, are arranged in series so as to constitute the two side walls and a central longitudinal wall 75 in the fire-box; with the alternate tubes 16 communicating with the portion of the drum or header formed by the section 8^a on the opposite side of the longitudinal center line of the fire-box and the portion of the header formed by the section 8 on the same side of the fire-box; while the alternate tubes 16^b, which constitute the other side wall of the fire-box, communicate with the portion of the drum or header formed by the section 8, located on the same side of the fire-box and with the portion or section 8^a located on the opposite side of the longitudinal center line of the fire-box, as very 85 clearly shown in Fig. 2. The alternate tubes 16^c, which constitute the intermediate or central longitudinal wall of the fire-box, communicate at their upper ends with the portions of the drum or header formed by the sections or members 8, 8, located on opposite sides of the fire-box; the upper ends of the water tubes 16^c, therefore, extend across the alternate tubes of the series 16, 16^b, as is very clearly shown in Fig. 2; the tubes 16^c therefore effect communication between the central longitudinal portion of the mud-ring and the side portions of the drum or header at the upper end of the fire-box.

95 With the construction shown and described, it is apparent that the water tubes 16, 16^b, and 16^c, or rather the alternate tubes of the series 16, 16^b, 16^c, form an open lattice work over the crown or top of the fire-box through which the hot gases circulate and 100 impinge against the bottom surfaces of the respective portions of the drum or header.

105 The water-tubes 16, 16^b, and 16^c, are preferably provided at their upper ends with a double reverse bend, see Fig. 2, in order to 110 give the least possible strain on the tubes due to unequal expansion and contraction. The water tubes may be secured in the sections of the drum or header in any approved manner, being preferably, however, welded 115 integrally therewith.

120 The ends of the sections 8, and 8^a, of the drum or header, extend throughout the entire length of the fire-box from flue-sheet to door-sheet, as clearly shown in Fig. 1; the 125 ends being properly secured to the flue sheet and the door-sheet so as to form a watertight connection, with the ends of the various sections of the header communicating with the water space of the boiler forward 130

of the flue-sheet and with the water space or leg intermediate of the door-sheet and back-head of the fire-box.

The door-sheet 18 and the back-head 19 are properly stayed together by means of stay-bolts 21, with the two sheets secured together by the rivet 22, with a calking strip 23 intervening.

In order that access may be had to the respective portions or sections of the top drum or header, the back-head 19 is shown provided with the drum-head 24 secured by the stud bolts 25 to the reinforcing ring 26 arranged about suitable openings in the back-head 19; the openings being arranged in alinement with the respective sections or portions of the drum or header, and the drum-head and ring are so formed as to provide suitable water-tight connections.

It is apparent from the construction that access to the various sections or portions of the header may be readily had to permit repair work on the water tubes by simply removing the drum-head or heads.

With the fire-box provided with a central wall of water tubes, the back-head of the fire-box and the door-sheet 19 and 18, respectively, are provided with two fire-doors, in order that proper access to both sides of the fire-box may be had; one of the fire-door openings being shown at 27 in Fig. 1.

As the sections or portions of the water-head do not entirely cover the upper portion of the fire-box, the spaces intermediate of the side sections or portions and the outer shell, may be provided with a fire-brick lining 28, see Fig. 2, which is shown held in place by suitable brackets 29, 29, secured to the flue-sheet and to the door-sheet on both sides of the fire-box, while the upper end of the fire-brick lining may be held in place by suitable brackets 30, 30, which may either be secured to the flue-sheet and door-sheet, or to the side sections, 8, 8, of the top header.

If desired, the fire-brick lining 28, may be extended down from the header-sections along the outside of the side water tubes 16 and 16^b, to the top of the mud-ring 15, that is, between the water tubes 16 and 16^b, and the outside wrapper sheet 31 at the respective sides of the fire-box.

It is apparent from the construction shown and described, that free circulation of the water may be had between the various sections or portions of the top-header, and the longitudinal sections or portions of the mud-ring, by means of the front and rear water-legs formed respectively by the throat-sheet 4 and flue-sheet 6 and the door-sheet 18 and the back-head 19, and also by means of the series of water-tubes 16, 16^b, and 16^c. It is also evident from the construction shown that circulation is had by means of the water tubes between the side water-heads of the mud-ring and the side sections or por-

tions of the top header and one of the intermediate sections or portions of the top header, namely the intermediate section farthest removed from the side of the fire-box from which the water tubes extend; 70 while the central wall of the mud-ring has communication by means of each alternate tube 16^c with the two side sections or portions of the top header 8.

As previously stated, the points of communication between the water tubes 16^c and the central longitudinal water head of the mud-ring, are preferably arranged in a staggered manner so as to provide a suitable bridge or metal portion in the mud-ring intermediate of the ends of the water tubes; 80 this method also permits a greater number of water tubes being connected to the respective water heads of the mud-ring as will be readily understood from the construction. 85

The front and back heads of the fire-box, which are in communication by means of the openings at the ends of the longitudinal sections of the mud-ring, convey ample water to the longitudinal hollow portions or sections of the mud-ring 15 to supply the circulating water to the water tubes 16, 16^b, and 16^c.

With my improved construction, it is apparent that a fire-box or combustion chamber is provided having an exceptionally large and efficient heating surface, namely a construction wherein the maximum amount of heat units may be absorbed by the water during its circulation through the respective 100 water tubes and top and bottom headers, thus resulting in a boiler capable of making steam very quickly and very rapidly; furthermore, the construction is such that all the water tubes as well as the top header 105 are readily accessible for purposes of repair, cleaning, etc., without the necessity of a complete dismembering of the fire-box.

The invention is shown applied to a locomotive type of fire-box, but it is evident 110 from the foregoing description as well as the drawings, that the invention may be readily applied to any style of boiler without, however, departing from the spirit of the invention, and the application is not 115 limited, therefore, to the exact construction shown and described.

What is claimed is:—

1. A fire-box, provided with top and bottom fluid-containing headers or members, 120 the top header or member being composed of a series of concavo-convex sheets constituting the lower wall thereof while the outer shell of the fire-box constitutes the upper wall of said header or member, and water 125 tubes arranged intermediate of the top and bottom headers or members so as to constitute the inner side walls of the fire-box and establish communication between said headers or members.

2. A fire-box, provided with top and bottom fluid-containing headers or members, the upper wall of the top header or member being formed by the outer shell of the fire-box while the bottom wall of said header is suspended from said outer shell so as to form a fluid-tight compartment, and water tubes vertically disposed intermediate of the top and bottom headers or members so as to establish communication between said headers or members at various points substantially throughout the entire length thereof.
3. A fire-box, comprising fluid-containing means longitudinally disposed in the upper and lower parts of the fire-box, the fluid-containing means in the upper part of the fire-box being formed by the outer shell of the fire-box and a lower wall suspended from said shell, and water tubes arranged intermediate of the top and bottom fluid-containing means so as to establish communication between said means, with the upper ends of the water tubes disposed to one side of the axes of said tubes and arranged in a criss-cross manner.
4. A fire-box, comprising top and bottom fluid-containing means arranged lengthwise of the fire-box, the top means being formed by the outer shell of the fire-box and transversely bent sheet of sheets having the sides secured to said outer shell, and water tubes vertically disposed between the top and bottom means so as to establish communication between said means.
5. A fire-box, provided with top and bottom fluid-containing headers or members, the top header or member being composed of a series of concavo-convex sheets constituting the lower wall thereof while the outer shell of the fire-box constitutes the upper wall of said header or member, means whereby the lower wall is yieldingly suspended from said shell, and water tubes arranged intermediate of the top and bottom headers or members so as to constitute the inner side walls of the fire-box and establish communication between said headers or members.
6. A fire-box provided with a front and rear water-leg, top and bottom fluid-containing means open at the ends thereof and in communication with said water-legs and with the water space of the boiler, the top means being formed by the outer shell of the fire-box and by transversely bent sheets having their sides secured to said outer shell, and water tubes vertically disposed between the top and bottom means so as to establish communication between said means.
7. A fire-box provided with fluid-containing means longitudinally disposed in the upper and lower parts of the fire-box, the fluid-containing means in the upper part of the fire-box being formed by the fire-box shell and a lower wall suspended therefrom, and water tubes arranged intermediate of the top and bottom fluid-containing means for establishing communication between the top and bottom fluid-containing means.
8. A fire-box, provided with top and bottom fluid-containing headers or members, the top header or member being composed of a series of concavo-convex sheets constituting the lower wall thereof, while the outer shell of the fire-box constitutes the upper wall of said header or member, sling-stays whereby said sheets are suspended from the outer shell of the fire-box, and water tubes arranged intermediate of the top and bottom headers or members so as to constitute the inner side walls of the fire-box and establish communication between said headers or members.
9. A fire-box, provided with top and bottom fluid-containing headers, the top header being composed of a series of concavo-convex sheets constituting the lower wall thereof while the outer shell of the fire-box constitutes the upper wall of said header, stay-sheets or members secured intermediate of the adjacent sides of the concavo-convex sheets, sling-stays pivotally secured to said stay-sheets or members and to the outer shell of the fire-box whereby the lower wall of the top header is suspended, and water tubes arranged intermediate of the top and bottom headers so as to constitute the inner side walls of the fire-box and establish communication between said headers.
10. A fire-box of the class described, comprising top and bottom fluid-containing means arranged lengthwise of the fire-box, the top means being formed by the outer shell of the fire-box and by transversely bent sheets having the sides secured to the outer shell and to intervening stay-sheets or members, and water tubes vertically disposed between the top and bottom means so as to establish communication between said means.
11. A fire-box of the class described, comprising fluid-containing means longitudinally disposed in the upper and lower parts of the fire-box, the fluid-containing means in the upper part of the fire-box being formed by the outer shell of the fire-box and a lower wall composed of transversely bent sheets, stay-sheets or members secured intermediate of the adjacent sides of said sheets, sling-stays pivotally secured to said stay-sheets or members and to the outer shell whereby the lower wall is suspended from the shell, and water tubes arranged intermediate of the top and bottom fluid-containing means so as to establish communication between said means, with the upper ends of the water tubes disposed to one side of the axes of said tubes and arranged in a criss-cross manner.
12. A fire-box of the class described, provided with top and bottom fluid-containing

headers, the top header being composed of a series of concavo-convex sheets constituting the lower wall thereof while the outer shell of the fire-box constitutes the upper 5 wall of said header, water tubes arranged in series intermediate of the top and bottom fluid-containing headers and in communication therewith, one of the series of said water tubes constituting a longitudinally 10 disposed central wall in the fire-box while the other series constitute the inner side walls of the fire-box, the alternate tubes of the series constituting the central wall of the fire-box being arranged in communication 15 with the portion of the top header composed of the sheets disposed along the sides of the fire-box while the alternate tubes of the series constituting the inner side walls 20 of the fire-box are arranged in communication with the sheets or portion of the top header arranged on the same side as the respective series and one of the intermediate sheets disposed on the opposite side of the longitudinal center line of the fire-box, and 25 means whereby the sheets constituting the lower wall of the top header are suspended from the outer shell of the fire-box.

13. A fire-box of the class described, provided with top and bottom fluid-containing 30 headers, the top header being composed of the outer shell of the fire-box and transversely bent sheets so as to provide a lower wall composed of two side and two intermediate concavo-convex portions, means whereby 35 said sheets are yieldingly suspended from the outer shell of the fire-box, and water tubes arranged intermediate of the top and bottom fluid-containing headers so as to establish communication between said headers, said water tubes being arranged in 40 series, one series constituting a longitudinally disposed central wall of the fire-box while the other series constitute the inner side walls of the fire-box, the upper end of 45 each alternate tube of all the series being in communication with a different portion of the top header.

14. A fire-box of the class described, provided with top and bottom fluid-containing 50 headers, the top header being composed of the outer shell of the fire-box and transversely bent sheets suspended from the outer shell, while the bottom header is formed by a mud-ring having hollow longitudinal portions, and water-tubes arranged in series intermediate of the top and bottom headers so as to constitute inner side walls and an intermediate wall, with the upper ends of the alternate tubes of the different series being 55 connected with a different sheet of the top header.

15. A fire-box of the class described, pro-

vided with top and bottom fluid-containing headers, the top header being composed of the outer shell of the fire-box and a plurality of transversely bent sheets, while the bottom header is formed by a mud-ring composed of two side and intermediate hollow longitudinal portions, and water tubes arranged in series intermediate of the side and intermediate longitudinal portions of the mud-ring and the sheets constituting the bottom wall of the top header, the upper ends of the tubes being arranged in a criss-cross manner so that the alternate tubes of the different series will establish communication between the respective longitudinal portion of the mud-ring and two transversely separated portions of the top header. 80

16. A fire-box of the class described, comprising a crown-sheet formed so as to provide a plurality of longitudinally disposed channels, means whereby said crown-sheet is removably stayed to the roof-sheet of the fire-box, a mud-ring provided with water-chambers in the longitudinally disposed portions thereof, and a series of water-tubes arranged intermediate of the chambers of the mud-ring and the channels of the crown-sheet, said water-tubes being arranged to constitute inner side walls for the fire-box. 90

17. A fire-box of the class described, provided with a front and rear water-leg, a crown-sheet formed of a plurality of separate channeled sections disposed longitudinally of the fire-box, means whereby said sections are secured together and supported from the roof-sheet of the fire-box, a mud-ring provided with hollow longitudinally disposed portions arranged to have communication with the front water-leg and the rear water-leg, and means intermediate of the upper surfaces of the hollow longitudinally disposed portions of the mud-ring and the respective channel-sections of the crown-sheet whereby circulation between the portions of the mud-ring and the crown-sheet may be established, said means being arranged to constitute the inner side walls 100 of the fire-box.

18. In a fire-box of the class described, provided with a crown-sheet composed of a plurality of channeled sections, members or anchor-bars secured to the roof-sheet of the fire-box and extending longitudinally thereof, and a plurality of sling-stays removably secured to said members or anchor-bars and to the sides of the respective channeled sections of the crown-sheet. 115

HENRY JACOBS.
